(57) **CLAIM**

The ornamental design for a clinical position tester for imparting electromagnetic radiation, as shown.

DESCRIPTION

FIG. 1 is a perspective view from the top, left and front of a clinical position tester for imparting electromagnetic radiation.

FIG. 2 is a front end view of the clinical position tester for imparting electromagnetic radiation of FIG. 1.

FIG. 3 is a rear end view of the clinical position tester for imparting electromagnetic radiation of FIG. 1.

FIG. 4 is a left side view of the clinical position tester for imparting electromagnetic radiation of FIG. 1.

FIG. 5 is a right side view of the clinical position tester for imparting electromagnetic radiation of FIG. 1.

FIG. 6 is a top plan view of the clinical position tester for imparting electromagnetic radiation of FIG. 1; and,
FIG. 7 is a bottom plan view of the clinical position tester for imparting electromagnetic radiation of FIG. 1.

The dashed lines showing the various parts of the clinical position tester for imparting electromagnetic radiation are for illustrative purposes only and form no part of the claimed design.
